United States Patent Office

Des. 211,820
Patented July 30, 1968

211,820

LUMINAIRE

Myron F. Pettengill, Hendersonville, N.C., assignor to General Electric Company, a corporation of
New York

Filed Nov. 8, 1967, Ser. No. 9,334

Term of patent 14 years

(Cl. D48—4)

Fig. 1

Fig. 2

I claim:

The ornamental design for a luminaire, as shown.
